(57) **CLAIM**

The ornamental design for a basketball shooting training device with side guides, as shown and described.

DESCRIPTION

FIG. 1 is a top perspective view of a basketball shooting training device with side guides, showing the new design;

FIG. 2 is a top view;

FIG. 3 is a bottom view;

FIG. 4 is a side perspective view;

FIG. 5 is a perspective view of the side opposite to FIG. 4;

FIG. 6 is a front perspective view; and,

FIG. 7 is a rear perspective view.

The broken lines of one or more of the FIGS. 1-7 are for illustrative purposes only and form no part of the claimed design.
